United States Patent Office.

E. H. BENJAMIN, OF OAK HILL, NEW YORK, ASSIGNOR TO GIFFORD, POTTER, AND COMPANY.

Letters Patent No. 79,051, dated June 23, 1868.

IMPROVEMENT IN SELF-LOCKING SHUTTER-HINGE.

The Schedule referred to in these Letters Patent and making part of the same.

TO ALL WHOM IT MAY CONCERN:

Be it known that I, E. H. BENJAMIN, of Oak Hill, in the county of Greene, and State of New York, have invented new and useful Improvements in Hinges for Window-Blinds and Shutters; and I do hereby declare that the following is a full, clear, and exact description thereof, which will enable those skilled in the art to make and use the same, reference being had to the accompanying drawings, forming part of this specification, in which—

Figure 1 is a front view of a window with my improved hinges.

Figure 2 is a top view of one of the hinges.

Figure 3 is the same view, but having the hinge in the position for lifting off or hanging the blind.

Figure 4 is a top view of the hinge when the blind is wide open.

Figure 5 is a section of fig. 4, through the line *x x* of that figure.

Similar letters of reference indicate corresponding parts.

This invention relates to certain improvements in window-blind hinges, whereby the same is held open by the automatic action of the hinge, as will hereinafter be more fully set forth.

In the drawings, A and B are the plates by which the hinge is attached to the blind, E, and window-casing D in usual manner.

The plate B is formed with a slotted projection, *b*, by which the pintle-plate P, which is made in a separate piece, and with a tongue, *i*, for fitting in the slot of the said slotted projection, is attached to the plate B, and when thus fitted, the pintle-plate and plate B form one part of the hinge.

The tongue *i* is shown fitting into and filling the slot at the sectional view of fig. 5.

Rising vertically from the pintle-plate is the pintle F, on which fits the eye of a projection, G, cast on the plate A.

This projection is provided with a hole, *d*, which catches, when the blind is opened, on a stud, *f*, formed on the pintle-plate P, whereby the blind is held open.

The formation of the hinge contributing to this operation of catching just mentioned, will now be set forth. The eye of the projection G is formed in part by a semi-cylindrical extension of the same, lettered *r*, which forms, with the adjacent part *m* of the eye, two shoulders, one of which is seen at *n*, fig. 1, the other being opposite thereto.

In fig. 2, the similar upper shoulders *n'* are shown, and though they do not conduce in any way to the action of the hinge, they indicate in the drawing the position of the lower shoulders, which are directly under them, and which limit laterally the same cylindrical extension.

Figure 5 exhibits the extension in the recess, the bottom of which latter being lower than the upper surface of the pintle-plate, on which the extension *r* impinges when the blind is closed, or before it has arrived completely back to the position shown in fig. 4, but when the blind does arrive in the last-named position, the lower end of the extension *r* passes from the surface of the pintle-plate, which sustained it, and drops by the weight of the blind into the recess, whereby the stud *f*, which was then brought directly under the hole *d*, passes through the said hole as the blind descends, and holds the latter from being blown to again.

When the blind is to be closed, it is simply necessary to raise it, so that the extension shall rise from the recess, when the blind can be drawn to.

The recess and extension contribute somewhat to the catching and holding of the blind, but the device which will resist the most violent action of the wind is the stud *f* and hole *d*, for, being somewhat removed from the centre of vibration of the blind, it offers increased resistance, and from the positive nature of its hold, it cannot become disconnected by the most violent and spasmodic gusts.

A stop, *s*, is formed on the plate B, as shown, for the purpose of keeping the eye down on its pintle, which

it does by encountering the rib *z*, formed on the extension *r*, when the blind is raised more than is required to lift the extension from the recess.

A notch, *o*, in the said rib, permits the blind to be lifted off or hung on the hinge.

Fig. 3 shows the blind in the proper position for being lifted off or hung on, for the notch *o* will permit the passage of the stop at that point and at no other.

The pintle-plate *P* is formed, as before stated, in a separate piece, and for two purposes, the first being that it can be more cheaply and easily made in that manner by casting or stamping, and the second being that it is then reversible, and can be placed in a contrary direction to that shown in the drawing, whereby the same hinge is available for a right or left-hand blind, and the parts can be taken indiscriminately and fitted as for a right or left blind, as circumstances require.

A second stop, *s'*, is formed in a proper corresponding position for operating in a like manner to the stop *s* above described.

The pintle-plate is held down upon the projection *b* by a screw, *k*, fitting, when screwed up, against a raised semicircular rib, *g*.

This rib is just at and above an oblong hole or slot for the screw *k*, and the concave side of the rib being bevelled to correspond to the bevelled heads of the ordinary wood-screws used for hinges, it will actuate the head of the screw downward as the latter is screwed against it, whereby the lower edge of the screw-head is made to bear upon the pintle-plate, for the oblong hole or slot will permit such downward actuation of the screw-head by the said rib.

The pintle-plate can thus be clamped firmly, and its tongue, *i*, fitting with finished contact within the slot of the projection *b*, conduce to the firm attachment of the pintle-plate.

When the pintle-plate is to be reversed in the manner before described, it is only required to withdraw the screw when the proportionate dimensions of the tongue *i* and its slot, and those of the oblong hole or slot of the screw *k*, will permit the tongue *i* to be turned out laterally, and the pintle-plate removed, for the slot of the screw *k* and the slot of the projection *b* merge into each other, and are continuous and connected.

The hinge above set forth is simple, cheap, durable, and not liable to break.

I am aware that hinges have been made upon a principle of action remotely similar to mine, but they have been discarded in practice to a great extent from certain disadvantages attending their use.

My invention obviates such disadvantages and provides a hinge for the purpose set forth, which is perfect in its operation.

I claim as new, and desire to secure by Letters Patent—

1. The reversible pintle-plate *P*, provided with a curved recess, the pintle *F*, and pin *f*, and adapted to be secured to the arm *b* of the right-angular plate *B* by means of the tongue *i* and screw *k*, all constructed and arranged as described, for the purpose specified.

2. The perforated projection *G* cast upon the plate *A*, and provided with the notched rib *z* and semicircular extension *r*, in combination with the recessed pintle-plate *P* and right-angular plate *B*, having the stops *S S'*, all constructed and arranged as described, to produce a reversible shutter-hinge, as herein set forth.

3. The semicircular rib *g*, or its equivalent, substantially as shown and described, in combination with the screw *k* and pintle-plate *P*, for the purpose of holding the latter firmly, all as set forth.

4. The tongue *i* of the pintle-plate *P*, or its equivalent, substantially as shown and described, in combination with the slotted projection *b*, for the purpose of permitting the firm attachment of the pintle-plate, all as set forth.

The above specification of my invention signed by me, this 3d day of December, 1867.

E. H. BENJAMIN.
